TOY PROJECTILE

Armand J. Leclerc, Leominster, Mass.

Application December 5, 1957, Serial No. 700,810

1 Claim. (Cl. 273—106)

This invention relates to a new and improved toy projectile in the nature of a molded plastic bullet for toy guns and simulated firearms of the type which eject a projectile toward a target etc., usually under spring compression.

The principal object of the present invention is to provide a safe, relatively soft and resilient but bodily self-sustaining elastic hollow bullet or projectile for the purpose stated, to the end that the bullet although projected with some force will not break articles or injure anyone struck thereby but at the same time the projectile will be stiff enough, i.e. self-sustaining, in order to function properly in the projecting apparatus as for instance including the compression spring which is released in order to provide for the ejection of the bullet or projectile through the barrel of the toy gun.

Other objects of the invention include the provision of a toy bullet as above described made of molded plastic, e.g., polyethylene, for proper elasticity, strength and softness and including a new and improved hollow member in the shape of a bullet or ball cartridge having a reduced forward end portion, said forward end portion being reduced in thickness toward a central opening therefor which provides a very soft forward portion for the bullet, preventing damage or injury under impact of the special soft, forward portions thereof.

Other objects and advantages of the invention will appear hereinafter.

Reference is to be had to the accompanying drawings, in which

Fig. 1 is a view in side elevation of the new projectile;

Fig. 2 is an end view, looking in the direction of arrow 2 in Fig. 1;

Fig. 3 is an opposite end view on an enlarged scale, looking in the direction of arrow 3 in Fig. 1;

Fig. 4 is a longitudinal sectional view, taken on line 4—4 of Fig. 2;

Fig. 5 is a view similar to Fig. 1 but showing the bullet impinging upon a solid surface; and

Fig. 6 is a greatly enlarged sectional view illustrating the forward portion of the bullet and the construction thereof.

In carrying out the present invention, the bullet or projectile comprises a molded plastic hollow body preferably using polyethylene or some similar substance in the molding operation to provide a resilient, elastic, deformable but self-sustaining object. This is shown in Figs. 1 to 4 inclusive as a generally cylindrical hollow body generally indicated by the reference numeral 10. The wall thickness thereof is comparatively slight but is made

2

sufficient for the self-sustaining function and also to provide enough body to the material so as to simulate a real bullet or ball cartridge.

At the forward end of the bullet or projectile, the same is rounded and blunt and provided with a reduced opening indicated at 12. This opening is formed by the surrounding wall material at the edge portion 14 thereof which is suitably reduced or thinned down and inwardly directed, see particularly Figs. 4 and 6.

10 The opposite or rear end of the cylindrical bullet or projectile is completely open as at 16 and this end of the device may be square-ended or as desired. In this case it is the rear end 16 of the bullet which normally will contact the compression spring and itself is used to compress the spring. There is provided a relatively firm end portion not reduced in thickness as it is at the forward end at 14, but a very short circular recess at 18 may be made to receive and position the end of a coiled compression spring.

Fig. 5 shows the bullet striking a solid wall or the like indicated in broken lines as at 20. The impact is illustrated by the distortion and expansion of the material laterally as at 22. This distortion would not occur if the forward end of the bullet were not reduced as to 25 opening 12 and the material drawn down to the relatively fine edge as at 14. The effect of this, however, is that the bullet absorbs the impact and it does not break windows or small objects as would otherwise be the case; however, at the same time toy soldiers and other miniature objects 30 may be knocked over by the new resilient bullet.

It will be seen that this invention provides an all-plastic, molded, one-piece unitary elastic projectile for use in toy firearms, the same being resilient and deformable and being completely safe both from the standpoint of break- 35 age of fragile articles and injury to anyone who may possibly be struck by the novel bullet.

Having thus described my invention and the advantages thereof, I do not wish to be limited to the details herein disclosed, otherwise than as set forth in the claim, but

40 what I claim is:

A toy projectile comprising a resilient plastic one-piece hollow cylindrical elastic body, the body being open at both ends and from end-to-end and having a wall of generally uniform section, said wall section being of 45 slight thickness compared to the over-all diameter of the body, the latter being easily deformable but normally self-sustaining, one end of the body being rounded and blunt, the wall of the body at said blunt end being gradually reduced in thickness to a relatively fine edge, the wall adjacent said edge being inwardly directed on a 50 curve to form the said rounded end, the opening at said rounded end being reduced in diameter relative to the inner diameter of the body, and said rounded end and reduced wall thickness at the rounded end forming a relatively softer forward nose for the projectile.
